(57) **CLAIM**

I claim the ornamental design for a universal rat measuring stick, as shown and described.

DESCRIPTION

FIG. 1 is a top perspective view of the universal rat measuring stick of the present invention;
FIG. 2 is a front elevational view of the universal rat measuring stick of the present invention;
FIG. 3 is a right hand side elevational view of the universal rat measuring stick of the present invention;
FIG. 4 is a bottom perspective view of the universal rat measuring stick of the present invention;
FIG. 5 is a rear elevational view of the universal rat measuring stick of the present invention;
FIG. 6 is a left hand side elevational view of the universal rat measuring stick of the present invention;
FIG. 7 is a top perspective view of the universal rat measuring stick of the present invention being used to measure a first rat having a first length; and,
FIG. 8 is a top perspective view of the universal rat measuring stick of the present invention being used to measure a second rat having a second length.
